UNITED STATES PATENT OFFICE.

THOMAS M. KENNEY, OF CAMBRIDGE, MASSACHUSETTS, ASSIGNOR TO THE AMERICAN STORE SERVICE COMPANY, OF NEW YORK, N. Y.

CASH-CARRIER.

SPECIFICATION forming part of Letters Patent No. 416,924, dated December 10, 1889.

Application filed May 21, 1887. Serial No. 238,962. (No model.)

To all whom it may concern:

Be it known that I, THOMAS M. KENNEY, of Cambridge, county of Middlesex, State of Massachusetts, have invented an Improvement in 5 Cash-Carriers, of which the following description, in connection with the accompanying drawings, is a specification, like letters on the drawings representing like parts.

My invention relates to a cash-carrier of 10 that class in which the carrier or receptacle is propelled along a track consisting of a stretched wire or cord, and the invention consists, mainly, in the novel construction of the motor for propelling the carrier.

15 The motor consists, essentially, of a sliding device normally engaged with the carrier when at the station, and a hand-actuated spring connected with the said slide-bar in such manner that when the spring is strained 20 it presses the bar against the carrier. The bar is restrained from moving when thus pressed upon by means of a locking device, which is disengaged and releases the carrier when the spring is sufficiently strained to 25 propel the carrier to the remote station.

Figure 1 is a side elevation of cash-carrier apparatus embodying this invention, showing the devices, in full lines, in the position occupied when the carrier is at the station and 30 while the actuating-spring is being strained, and in dotted lines in the position occupied at the moment that the carrier is released; and Fig. 2 a front elevation of the apparatus at the station.

35 The track *a* is shown as consisting of a wire or cord extending from one to the other of the points or stations between which the cash or other material is to be conveyed, the said track being fastened at its ends to any convenient support. At the stations at the ends of the track *a* the latter passes through a bracket *b*, which may be supported from the ceiling or any other suitable support, being shown as screwed upon the end of the rod *b'*. The 40 said bracket *b* is provided with a guide *b*² for the sliding device or propelling-bar *c*, which is free to move in said guide in a direction parallel with the track *a*, and is provided at its forward end with a carrier-engaging portion *c'*, (shown as a fork,) that engages a portion 45 of the frame *d* of the carrier, said frame

d being hung from grooved wheels *d'*, that run on the track *a*, and having at its ends downwardly-projecting arms *d*², that co-operate with the propelling mechanism at the station. 55

The box or receptacle *d*³ for the cash or other articles or material to be conveyed is shown as a cylinder closed at its lower end, adapted to be connected by a suitable fastening with a cap-plate *d*⁴, preferably pivoted to the frame *d*, so that the said receptacle is free to swing on the said frame *d*. The fastening of the receptacle *d*³ to the cap-plate or head-piece *d*⁴ is shown in this instance as effected by means of pins or projections *d*⁶ on the said receptacle that engage with curved arms *d*⁷ on the head-piece *d*⁴, so that by placing the pins *d*⁶ above the ends of said arms *d*⁷ and then turning the receptacle 70 *d*³ about quarter around said receptacle will be held securely up to the head-piece *d*⁴; but it is obvious that any other suitable catch or fastening might be employed to hold the receptacle *d*³ on the carrier-frame *d*. 75

The arms *d*² at the end of the carrier-frame are provided with inclined striking faces or cams *d*⁸, which, when the carrier comes into the station, engage a locking device *e*, pivoted at *e'* on the bracket *b*² and normally held by a spring *e*² against a stop *e*³ in position to engage the arm *d*² and prevent the carrier from moving away from the station, as shown in Fig. 1, although the said locking device is turned by the engagement of the inclined 85 faces or cams to permit the arm *d*² to pass by it as the carrier comes into the station.

For the purpose of propelling the carrier away from the station with a force sufficient to send it into the station at the other end of the track, the propelling slide-bar *c* is engaged by a spring *f*, provided with means for straining it so as to press the bar *c* against the carrier in the direction to propel the latter along the track. The carrier cannot, however, move under the action of this pressure until disengaged from the locking device *e*, which disengagement takes place when the spring is strained the proper amount to give the desired propelling impulse. In order to 90 properly strain the spring and disengage the carrier at the proper moment, the said spring is 95 100

connected with an actuating-band f' , (shown as connected with the drum or pulley g), having connected with it a second drum or pulley g' , to which is attached an actuating-cord g^2 provided with a suitable handle g^3 , accessible to the operator. Thus by pulling down the handle g^3 the pulleys $g' g$ are turned and the band f' wound upon the latter, thus straining the spring f .

10 The locking device e is provided with an arm e^4 at the opposite side of its pivot from the part that engages the arm d^2 of the carrier, which arm e^4 is provided with pins or projections e^5 , embracing the band f' , which latter is provided with a projection f^6 , which, in the movement of the band by which the spring f is strained, engages the said projections e^5 , and thus turns the locking device e in the direction to release the carrier, as shown 15 in dotted lines, Fig. 1, and the moment that the carrier is thus released the spring f acts to move the slide-bar c and carrier along the track, giving the latter sufficient impetus to propel it to the other station. The slide-bar c may then remain in its forward position until the carrier returns, when the latter will engage the forward end of the said slide-bar and move the latter back to its normal position, (shown in Fig. 1,) simply unwinding the 20 band f' and winding up the cord g^2 without straining the spring f .

25 It is obvious that the band f' might itself extend over the pulley and be provided with the actuating-handle instead of using a separate actuating-cord g^2 ; but by using the two pulleys, as shown, any desired relation between the force of the spring f and the force required to be applied to the handle g^3 to strain it may be attained, and thus a very

stiff quickly-acting spring may be used without requiring too great force to be applied by the operator to the handle g^3 .

In many cases the track a will be arranged in an inclined position, in which case the propelling device at the lower end will have sufficient force to propel the carrier up the incline, and it may be returned by a weaker propelling device, or by gravity alone if the incline is sufficient, in which latter case no propelling device will be required at the 45 higher end of the track.

I claim—

1. The combination of the track a and bracket b , located near one end thereof, the propelling slide-bar longitudinally movable 55 in a guide in said bracket, and the actuating-pulley and locking device pivotally supported in said bracket below said slide-bar, a band connected with said pulley and with a spring, which spring is connected with said slide-bar, 60 and a tripping projection on said band, said locking device having a shoulder at the front of the pulley to engage with the carrier, and an arm at the rear of the pulley to engage the said projection on the band, substantially as 65 and for the purpose described.

2. The combination, with the locking device e , of the propelling-slide c and its actuating-spring f , and the band f' and cord g^2 and connected pulleys $g' g$, to operate substantially as described.

In testimony whereof I have signed my name to this specification in the presence of two subscribing witnesses.

THOMAS M. KENNEY.
